UNITED STATES PATENT OFFICE

RAYMOND C. BENNER, OF NIAGARA FALLS, NEW YORK, ASSIGNOR TO THE CABORUNDUM COMPANY, OF NIAGARA FALLS, NEW YORK, A CORPORATION OF PENNSYLVANIA

FURNACE

Application filed December 13, 1927. Serial No. 239,724.

This invention relates to furnaces and to the method of operating them, and constitutes an improvement on the invention disclosed in the application of Clarence E. 5 Hawke, Serial No. 244,734, filed January 5, 1928.

In the said application of Clarence E. Hawke it is pointed out that with the present improved fuel burning apparatus and 10 furnace designs the number of B. t. u.'s/cubic foot/hour in the combustion space has been increased enormously over the rating of boilers according to old methods of burning fuel and old designs of furnaces. This enormous increase in the rate of fuel combustion 15 per cubic foot per hour imposes very severe operating conditions on the furnace linings.

In the said Hawke application provision is made for protecting the linings by 20 structuring the linings of a refractory material which is many times more thermally conductive than fire clay, and which is much stronger at operating temperatures than fire clay, and the temperature of this lining is 25 controlled by the circulation of air back of the unexposed face of the lining. By the selection of a refractory material whose rate of thermal conductivity is in excess of .006 cal/cm³/°C./sec., designing the lining of a 30 suitable thickness, and by forcing air back of the lining at a predetermined rate, a definite control of the temperature on the face of the lining is secured. It is possible to keep the exposed face of the lining at a 35 temperature considerably below the flame temperature of the furnace and below the congealing point of slag and ash. By so controlling the temperature, the ash and slag will congeal on the exposed face of the lining and form a protective film or coating 40 resistant to the erosive action of hot slags and ash.

It is also pointed out in said application that the control of the temperature at the 45 face of a fire clay lining is not practical because fire clay has a heat conductivity of less than .006 cal/cm³/°C./sec. and that any wall of fire clay thin enough to allow for any appreciable control would not have the 50 mechanical strength to sustain itself at the

operating temperature of the furnace. In said application there is disclosed the provision of a lining of a refractory such as silicon carbide whose thermal conductivity ranges between .029 and .038 cal/cm³/°C./sec. 55 The silicon carbide, in addition to having a high coefficient of thermal conductivity as compared with fire clay and other materials, also has considerable strength at the operating temperatures encountered in furnaces. 60

In order for a fire clay wall to have the same thermal conductivity as a silicon carbide wall, it would have to be very much thinner than the silicon carbide wall. Walls 65 of various refractories having equal thermal conductivity, which means unequal wall thickness, would have the following properties: 70

	SiC	Fused Al ₂ O ₃	Magnesite	Clay	
Thermal conductivity	Same.	Same.	Same.	Same.	
Thickness	9	2.5	2.5	1	
Transverse strength	59,700	1,250	875	200	75
Crushing strength	6,300	500	125	50	
Resistance to fused ash	63	2.5	1	1	
Resistance to abrasion	18.9	5	0.02	1	
Resistance to spalling	6.3	1.3	0.7	1	
Fusion point	2240° C.	1900° C.	1900° C.	1750° C.	

From the foregoing it becomes apparent 80 that control of the temperature at the exposed face of a fire clay wall by the circulation of fluid back of the wall is not practical.

As pointed out in the said Hawke application, control of the temperature at the exposed face of the refractory is highly desirable for the most efficient conditions of operation. Not only is it possible to afford greater protection of the refractory by keeping this exposed face below the congealing point of 85 the slag, but it is also possible to keep the interior of the furnace at a temperature sufficiently high to secure a high rate of combustion and a thorough combustion of the fuel. Where control of the temperature on 90 the exposed face of the lining is not possible, it is necessary to depress the flame temperature in the combustion chamber by an excess amount of air, or it is necessary to make the combustion space excessively large in order 95 100

that the walls will be remote from the flames. Excessive cooling of the furance walls, as where a water screen is used, interferes with efficient combustion particularly where powdered or suspended fuels are being burned because such fuels burn with the greatest efficiency only where the temperature of the walls of the combustion space is relatively high.

With the practice of the invention as disclosed in the said Hawke application, a considerable degree of control is possible, and the air which is used in cooling the furnace lining is supplied to the furnace for supporting combustion, thereby further increasing the efficiency of the furance. However, under some conditions of operation it is desirable to provide some means of cooling in addition to the air.

According to the present invention the air cooling of a lining is combined with other cooling means for securing a greater degree of control. According to the preferred embodiment of the invention the cooling means may also be used to reinforce the wall structure and thereby not only increase the degree of temperature control which may be exercised but also add to the mechanical strength of the lining.

The invention may be readily understood by reference to the accompanying drawing, in which

Figure 1 is a more or less diagrammatic view representing a cross section through a boiler provided with a powdered coal-burning furnace and embodying the present invention;

Figure 2 is a detail view representing a section through a wall constructed according to a preferred embodiment of my invention;

Figure 3 is a view similar to Figure 2 of a modified arrangement; and

Figure 4 is a view similar to Figure 2 of another modification.

The arrangement shown in Figure 1 is a typical powdered coal burning installation applied to a boiler furnace. In this view, 2 is the pulverizer fan for feeding powdered coal from a hopper 3 through a feeder pipe 4 into the combustion space 5 of the furnace, designated generally as 6. The boilers are outlined at 7. The interior of the combustion chamber 5 is lined with a refractory material having a coefficient of thermal conductivity which is relatively high as compared with fire clay, its thermal conductivity being in excess of .006 cal/cm³/°C./sec. This lining is preferably made of silicon carbide and is designated 8. Between the wall 8 and the outer shell 9 of the furnace is an air circulating space 10. Air is supplied to the space 10 by a fan 11 which forces the air through a pipe 12 into an opening 13 communicating with the space 10. The air which is forced or circulated through the space 10 at a pre-

determined rate, is discharged through a pipe 14 which communicates with a chamber 15 surrounding the turbulent burner 16 at the end of the pipe 4, the arrangement being such that the air which is forced through the space 10 between the silicon carbide wall and the outer shell of the furnace may be discharged with the fuel into the combustion chamber. The primary or compressed air line for the burner is designated 17.

So much of the arrangement as has been described is disclosed in the said Hawke application. According to the present invention, pipes or conduits are built into the air circulating passage. Fluid can be circulated through these pipes. The pipes will receive heat directly from the furnace lining by radiation, and heat will be transferred from the furnace lining to the pipes and to the fluid circulating therethrough by the air wiping against the lining and then against the pipes. The temperature of the air can thus be controlled and greater cooling secured. The pipes may be located at certain points about the lining where there is a particular tendency of the lining to become overheated, or can be located throughout the entire lining.

In Figure 1 there is illustrated one possible arrangement wherein there are a plurality of vertically extending pipes 18 connected to a common header 19 at the top thereof, and to a similar header 20 at the bottom thereof. Water or other cooling fluid may be supplied to the header 19 through a pipe 21 and valve 22, and water may be withdrawn from the header 20 through pipe 23 and valve 24, or the circulation of fluid can be reversed.

Figure 2 illustrates a preferred arrangement of the pipes in the air circulating passages. In Figure 2, 25 designates a furnace lining of silicon carbide or other refractory having a high coefficient of thermal conductivity as compared with fire clay. The exposed face of the lining is designated 26 and 27 designates the fire clay or other shell outside the lining 25. In the lining 25 are a plurality of air circulating passages 28 through which air can be forced through the blower. Arranged in some or each of the passages 28 is a pipe 29 through which water, steam or other fluid may be circulated. The pipes 29 receive heat from the refractory 25 by direct contact with the refractory. They also receive heat by radiation from the refractory, and the refractory is cooled by the transfer of heat from the air circulating through the passages 28 to the pipes. Due to the wiping action which the air has over the surface of the refractory material and over the surface of the pipes, the heat is transferred very efficiently. By regulating the flow of air and the flow of fluid the temperature of the air can be controlled and the

rate of heat dissipation from the face 26 can be governed.

In addition to this the pipes 28, as shown in Figure 2, serve to reinforce the wall 25 and impart added mechanical strength thereto.

In the arrangement shown in Figure 3 the fluid circulating pipes, designated 30, are located in a passage 31 between the refractory lining 32 of silicon carbide or other refractory having a high coefficient of thermal conductivity, and the outer shell 33. The exposed face of the lining 32 is indicated by the reference numeral 34. The arrangement shown in Figure 3 is generally similar to that outlined in Figure 1. The pipes in this arrangement being staggered, impart a turbulent flow of the air so that there is a greater wiping action against the unexposed surface of the refractory 32 and against the outsides of the pipes. The pipes also receive heat by radiation directly from the refractory 32.

In the arrangement shown in Figure 4, 35 designates the exposed surface of a furnace wall which possesses a much higher coefficient of heat conductivity than fire clay, such for instance as silicon carbide. The wall itself is designated 36 and at 37 is the usual fire clay wall at the unexposed surface. Formed in the wall 36 are water circulating pipes 38. The wall 36 also has air circulating passages 38a therein. This construction differs from that shown in Figures 2 and 3 in that the water and air circulating passages are separated. In this construction, as in the constructions previously described, more effective control of the temperature of the furnace wall can be secured than where one fluid alone is used for cooling the wall. The water pipes furthermore serve to reinforce the wall.

The invention provides for a more efficient cooling of the refractory than is possible where water cooling or air cooling is relied upon entirely, and provides for a more accurate control of the temperature conditions at the exposed face of the lining. It is necessary in order to secure this control that the refractory lining have a high coefficient of thermal conductivity as compared with fire clay so that heat may be transferred therethrough at a rate sufficient to secure a material difference between the exposed face of the lining and the flame temperature. At the same time it is necessary that the wall be thick enough to have the desired mechanical strength. The pipes for the circulation of water or other fluid can be located wherever they are needed. If additional cooling is necessary for only certain parts of the lining, the pipes can be disposed adjacent those parts only.

The invention is particularly applicable to the burning of powdered coal or suspended fuels where the most efficient conditions of combustion are obtainable when the lining is at a temperature substantially above 400° C.

In the burning of such types of fuels also the furnace lining is subjected to the most severe conditions of operation and the control of the temperature at the face of the lining is therefore more desirable.

While I have described and shown certain embodiments of the invention it will be understood that this merely is by way of illustration and the invention is not confined to the particular arrangement and construction shown as various changes and modifications may be made within the contemplation of the invention and under the scope of the appended claims.

I claim:

1. In a furnace, a combustion chamber having a wall with a refractory lining comprised principally of silicon carbide, said lining having a thermal conductivity many times that of fire clay, water-tight conduits in said wall structure, an air passage in said wall structure, and means for forcing a current of air through said air passage.

2. In a furnace, a combustion chamber having a wall structure with a lining of a non-metallic refractory, the thermal conductivity of which is in excess of .006 cal/cm³/°C./sec., water-tight conduits in said wall structure, an air passage in said wall structure, and means for forcing a current of air through said air passage, said water-tight conduits being located directly in the air passage whereby the current of air will wipe over the surface of said water-tight conduits.

3. In a furnace, a combustion chamber having a wall structure with a lining of a non-metallic refractory material comprised principally of silicon carbide and having a thermal conductivity in excess of .006 cal/cm³/°C./sec., water-tight conduits in said wall structure, an air passage in said wall structure, and means for forcing a current of air through said air passage, said water-tight conduits being located directly in the air passage whereby the current will wipe over the surface of said water-tight conduits.

4. In a furnace, a combustion chamber having a wall structure with a lining of a refractory material comprised principally of silicon carbide the thermal conductivity of which is in excess of .006 cal/cm³/°C./sec., water-tight conduits in said wall through which fluid may be circulated, an air passage in said wall back of the exposed face thereof through which a current of air may be circulated, a blower at the input end of said air passage for blowing air through the air passage and maintaining a pressure in said passage above atmospheric pressure.

5. In a furnace, a refractory wall structure having a lining comprised principally of silicon carbide, the thermal conductivity of which lining is in excess of .006 cal/cm³/°C./sec., a water-tight conduit in said wall structure

back of the exposed face of the lining, an air passage in said wall structure back of the exposed face of the lining, means for forcing a current of air through said air passage, said water-tight conduits being located directly in the air passage, and means for conducting substantially all of the air from said passage to the combustion chamber to support combustion therein.

10 6. In a furnace, a wall structure having a lining comprised of a refractory material the thermal conductivity of which is in excess of .006 cal/cm³/°C./sec., water-tight conduits in said wall structure, an air passage in said wall structure, and means for forcing a current of air through said air passage.

15 7. In the method of controlling the temperature of a non-metallic refractory furnace lining having a thermal conductivity in excess of .006 cal/cm³/°C./sec., the steps which comprise conducting heat from the exposed face of the refractory at a rate sufficient to keep such face below the point at which the slag in the furnace is fluid by circulating air 20 against an unexposed face of said wall, and cooling the air as it circulates against the unexposed face to reduce the volume of air required.

25 8. In the method of controlling the temperature of a non-metallic refractory furnace lining having a thermal conductivity in excess of .006 cal/cm³/°C./sec., the steps which comprise conducting heat from the exposed face of the refractory at a rate sufficient to 30 keep such face below the point at which the slag in the furnace is fluid by circulating air against an unexposed face of said wall, cooling the air as it circulates against the unexposed face to reduce the volume of air required, and utilizing all of the air so circulated in the furnace to support combustion.

35 9. In the method of controlling the temperature of a non-metallic refractory lining in a boiler furnace wherein the lining has a high thermal conductivity as compared with a fire clay refractory and in excess of .006 cal/cm³/°C./sec., the steps which 40 comprise conducting heat from the exposed face of the refractory at a rate sufficient to keep such face below the point at which the slag in the furnace is fluid by circulating air against an unexposed face of the wall, cooling the air as it circulates against the unexposed face by simultaneously circulating it over conduits 45 which contain the fluid contained in the boiler to reduce the amount of air required, and utilizing all of the air to support combustion in the furnace.

40 10. In the method of controlling the temperature of a non-metallic refractory furnace lining having a high thermal conductivity and in excess of .006 cal/cm³/°C./sec., the steps which comprise conducting heat from the exposed face of the refractory at a rate 45 sufficient to keep such face below the point at

which the slag in the furnace is fluid by transferring heat from an unexposed surface of the wall to a confined fluid and simultaneously wiping an unexposed face of the wall with a current of air, and controlling the temperature of the exposed face by varying the volume of air circulated. 70

11. In the method of controlling the temperature of a non-metallic refractory furnace lining formed principally of silicon carbide, 75 the steps which comprise conducting heat from the exposed face of the silicon carbide refractory at a rate sufficient to keep such face below the point at which the slag in the furnace is fluid by transferring some of the heat from the wall to a confined fluid and transferring other heat to air wiping against an unexposed face of the wall, and maintaining the pressure of the air which wipes the unexposed face of the wall at a pressure above 80 atmospheric pressure. 85

12. In the method of controlling the temperature of a non-metallic refractory furnace lining formed principally of silicon carbide, 90 the steps which comprise conducting heat from the exposed face of the silicon carbide refractory at a rate sufficient to keep such face below the point at which the slag in the furnace is fluid by transferring some of the heat from the wall to a confined fluid and transferring other heat to air wiping against an unexposed face of the wall, and varying the volume of air circulated against the wall in accordance with the increase or decrease in the fluidity of the slag contacting with the wall. 95 100

13. A furnace wall comprising, in combination, a lining of silicon carbide on the inner side of the wall, an outer portion constructed of fire clay, ducts in the silicon carbide lining for the circulation of cooling media in heat 105 interchanging relation, said ducts including water pipes subjected to the wiping action of controlled current of air surrounding said pipes, and means for circulating air at controlled velocity relative to said pipes. 110

14. In a furnace, a combustion chamber having a wall structure with a lining of non-metallic refractory material the thermal conductivity of which is in excess of .006 cal/cm³/°C./sec., water-tight conduits 115 in said lining said conduits supporting the lining and being in substantial contact therewith for a material proportion of the area of the conduit, an air passage within the wall, and means for circulating air through said 120 passage and in contact with said lining and said conduits.

15. In the method of controlling the temperature of a non-metallic refractory furnace lining formed principally of silicon carbide, 125 the steps which comprise conducting heat from the exposed face of the silicon carbide refractory at a rate sufficient to keep such face below the point at which the slag in the furnace is fluid by transferring some of the heat 130

from the wall to a confined fluid, and transferring other heat to air wiping against an unexposed face of the wall, and maintaining the pressure of the air which wipes the unexposed face of the wall at a pressure above the pressure within the furnace to prevent the suction of any hot furnace gases through the refractory wall.

In testimony whereof I have hereunto set
my hand.

RAYMOND C. BENNER.
